ABRADING ROLL

Earl E. Price, Minneapolis, Minn., assignor to
 G. H. Tennant Company, Minneapolis, Minn., a
 corporation of Minnesota

Original application July 1, 1935, Serial No.
 29,305. Divided and this application May 24,
 1937, Serial No. 144,426

4 Claims. (Cl. 15—230)

This invention relates to improvements in
 abrading rolls, composed of steel wool or func-
 tionally equivalent material, wound on a suitable
 base, and to a method of winding such rolls to
 produce a roll which will not cause streaking of
 the surface upon which it is used.

One of the problems in the art of making
 abrasive rolls by the use of steel wool has hereto-
 fore been to so wind the abrasive material as to
 prevent what is known as "streaking" of a floor
 or other uneven surface being cleaned or abraded
 by the roll. I have found that this streaking is
 due to uneven winding, or to such close packing
 of the material, during formation of the roll, that
 various parts thereof cannot yield conformably to
 inequalities in the surface being abraded or pol-
 ished.

I have found that streaking is largely overcome
 if a softer more yieldable core layer is initially
 formed or provided, and if a more unyieldable
 layer or cylinder of abrasive material is super-
 posed upon this softer cushioning layer. In this
 way, an inner cushion is provided which allows
 the various areas of the more hardly packed ma-
 terial to move inwardly and accommodate them-
 selves to the non-coplanar or upstanding ine-
 qualities in the surface being abraded or cleaned.

An important object of the present invention
 therefore, is to provide an abrading roll made of
 steel wool, or of any equivalent abrading mate-
 rial, which is so constructed that it is not likely
 to damage the surface being treated, by "streak-
 ing", as is frequently the case when using con-
 ventional abrading rolls, and whereby the opera-
 tion of refinishing the surface may be expe-
 dited.

A further and more specific object of the in-
 vention is to provide an abrading roll comprising
 an inner layer of a suitable cushioning material
 about which the outer abrading layer is wound,
 said inner layer forming a soft cushioning core
 for the outer layer whereby the latter may yield
 to irregularities in the surface being finished,
 and thereby prevent streaking or otherwise dam-
 aging the surface.

A further object is to provide a simple, inexpen-
 sive abrading roll, comprising an inner support-
 ing member having a suitable cushioning mate-
 rial wound thereon and surrounded by a layer of
 steel wool, which provides the abrading surface
 of the roll, said cushioning material permitting
 the steel wool to yield, when the periphery of
 the roll engages upstanding irregularities in the
 surface of the floor, thereby preventing the roll
 from streaking the surface.

This application is a division of my application
 Serial No. 29,305, now issued Patent No. 2,089,707.

Other objects of the invention will appear from
 the following description and accompanying
 drawing and will be pointed out in the annexed
 claims.

In the accompanying drawing there has been
 disclosed a structure designed to carry out the
 various objects of the invention, but it is to be
 understood that the invention is not confined to 10
 the exact features shown as various changes may
 be made within the scope of the claims which
 follow.

In the drawing:

Figure 1 is a perspective view of my improved 15
 abrading roll;

Figure 2 is a view, partially in section, showing
 the unique manner of winding the steel wool
 onto the supporting member, whereby the inner
 layer of steel wool serves as a soft cushioning core 20
 for the outer abrading layer; and

Figure 3 is a perspective view showing the inner
 supporting member about which the steel wool
 is wound.

The important feature of the present invention 25
 resides in the unique construction of the abrad-
 ing roll, whereby the outer surface or periphery
 thereof is rendered capable of yielding when the
 roll engages certain types of irregularities in the
 surface to be refinished, and whereby the danger 30
 of streaking the surface by the action of the roll
 is eliminated.

In the construction of the novel abrading roll
 herein disclosed, a tubular shell, generally in-
 dicated by the numeral 26, is provided, upon 35
 which the steel wool or other abrading mate-
 rial is wound. This shell may be provided with
 suitable prongs or fingers 40, to which one end
 of the steel wool may be attached, when start-
 ing the winding of the roll. The shell 26 is then 40
 rotated by suitable means such, for example,
 as the machine disclosed in my patent, herein-
 before mentioned, whereby the steel wool, which
 may be in the form of a ribbon or cord, is coiled
 about the core its entire length.

A light tension is applied to the steel wool that
 is first wound onto the shell, whereby a layer
 of steel wool, generally indicated by the numeral 50
 120, is provided on the shell 26. Because of the
 light tension applied to this first layer of steel
 wool, it is comparatively loose on the shell,
 whereby it may readily yield and thereby serve
 as a soft cushioning core for the outer layer
 of steel wool, subsequently to be wound there-
 about.

When sufficient steel wool has been wound about the shell 26 to provide the desired thickness for the cushioning core 120, greater tension is applied to the ribbon of steel wool being wound onto the soft core 120. This relatively greater tension is maintained until the roll has been completed, as shown in Figures 1 and 2. In the drawing I have indicated the outer portion or layer of the steel wool by the numeral 121. By 5 thus increasing the tension on the steel wool wound onto the first layer forming the cushioning core 120, the outer portion or layer 121 will be more dense in cross section than the inner layer 120, whereby it becomes more firm, 10 and will provide an efficient, wear-resisting abrading surface. The inner layer 120, being less dense in cross section, because of being wound onto the shell 26 with less tension, provides a soft cushion for the outer abrading surface of the roll, whereby streaking and otherwise marring of the surface to be treated is 15 entirely eliminated. This, as previously stated, results because of the outer surface of the roll being able to yield to any uneven or irregular 20 surface of the floor, as a result of the inner cushion member 120.

The novel abrading roll herein disclosed, has been found very practical and efficient in refinishing old floors. The inner layer 120 forms 25 a soft supporting base for the outer layer or abrading portion 121 of the roll. I have herein referred to the cushioning core 120 as being made of steel wool but it is to be understood that it may be made of any suitable material applicable for the purpose, which will retain the outer layer or portion 121 in concentric relation with the shell 26 and will permit the outer layer to yield to irregularities in the surface of the floor being treated. The cushioning 30 base or layer 120 is therefore, an important feature of the invention as, by its presence in the construction of the roll, the periphery of the roll may readily yield to pressure, whereby the danger of the periphery of the roll streaking the 35 floor is entirely eliminated.

To prevent the layers of steel wool or other material wound about the shell 26 from relatively shifting in a lengthwise direction thereof, suitable flanges 25 are preferably provided at the ends of the shell 26, and annular outwardly 40 projecting ribs 41 may also be provided thereon intermediate the ends of the shell. The ribs 41 and also the elements 40 are covered or concealed 45 by the inner soft layer 120 of the roll, as clearly illustrated in Figure 2. A cross bar 42 may be

provided in one end of the shell 26, as best shown in Figure 3 to facilitate handling the roll, and which may also function as a driving means between the shell and the mandrel or driven element upon which the shell is mounted, when the steel wool is wound thereabout. This mandrel or driving element is not illustrated in the drawing. 5

I claim as my invention:

1. An abrading roll comprising a suitable base 10 having two concentrically related inner and outer layers of steel wool surrounding it and suitably secured thereto in relatively fixed relation, the inner layer being less dense than the outer.

2. An abrading roll comprising a suitable base 15 having two concentrically related inner and outer layers of steel wool surrounding it and suitably secured thereto in relatively fixed relation, the inner layer being less dense than the outer, and the thickness of said inner layer being 20 less than the thickness of the outer layer.

3. An abrading roll comprising a tubular supporting member having outwardly turned flanges at its ends and provided with one or more annular ribs spaced apart lengthwise of the member, steel wool loosely wound on said member to cover the entire periphery thereof and to a predetermined thickness sufficient to conceal said annular ribs and providing a soft cushioning core, and additional steel wool wound about said 30 soft cushioning core under relatively greater tension, whereby the steel wool wound about said core is relatively more compact and dense than the steel wool forming the core, whereby the periphery of the roll will offer greater resistance 35 to wear, said relatively softer steel wool core permitting the abrading surface of the roll to yield and thereby eliminate streaking of the surface being treated or finished.

4. An abrading roll comprising a tubular supporting member, a layer of steel wool loosely wound on said member to cover the entire periphery thereof and providing a soft cushioning core, and another layer of steel wool wound about said soft cushioning core under relatively 45 greater tension, whereby the layer of steel wool wound about said core is relatively more compact and dense than the steel wool forming the core, whereby the periphery of the roll will have greater resistance to wear, said soft cushioning 50 core permitting the abrading surface of the roll to yield and thereby eliminate streaking of the surface being treated or finished.

EARL E. PRICE. 55.
